SHEET FEEDING MECHANISM

Henning Hallstream, Braintree, Mass., assignor
to Cross Paper Feeder Company, Boston, Mass.,
a corporation of Massachusetts

Application March 12, 1930, Serial No. 435,040
Renewed June 18, 1934

5 Claims. (Cl. 271—46)

The present invention relates to paper-feeding mechanism adapted for the regular and uniform delivery of sheets to a printing press or the like. The invention is particularly concerned with mechanism for accurately and expeditiously handling the sheets between separation from a bank or pile and delivery to the truing or pull-up guides for transfer to the press.

It is one object of the present invention to provide a mechanism which is capable of initiating and maintaining a positive engagement with the sheet during its transfer from a position adjacent the pile or bank to the pull-up guides, and to perform this transfer in a manner to avoid tearing or injury to the sheet independently of the rate of transfer.

It is a further object of the invention to provide a mechanism capable of satisfactorily handling and controlling sheets having the greatest variance in dimensions which may be found in commercial practice, and to maintain positive and accurate control of these sheets throughout the entire range of movement.

With these and other objects in view, one feature of the present invention contemplates the provision of delivery rolls which receive a sheet separated from a pile or bank by combing wheels, or their equivalent, these delivery rolls being positively operated in timed relation to the delivery of a sheet. The delivery rolls have a variable speed of operation according to a predetermined cycle such that the rolls have approximately the lowest or minimum peripheral speed at the instant of engagement with the front edge of a sheet delivered thereto by the separating mechanism. After delivery of the separated sheet to the positively driven rolls, the sheet is engaged in feeding relation by automatically-operated drop rolls which cause the forwarding of the sheet by the delivery rolls in an accurate and predetermined manner. Immediately after engagement of the sheet, the rate of speed of the rolls is accelerated and the latter caused to travel at substantially a maximum rate of speed during the transfer of the sheet to the pull-up or truing guide. Located between the delivery rolls and the pull-up guides to which the front end of the sheet is delivered are a set of what may be denominated as front delivery rolls, which function primarily for the purpose of maintaining a constant control of the sheet during its entire range of movement and slowing down or decelerating the advance of the sheet at the instant delivery to the pull-up guides. The front delivery rolls or tail-end slowdown, as it may be termed,

are adjustable lengthwise of the feeder, and are normally designed to be positioned in accordance with the size of the sheet to maintain control thereof until delivery to the pull-up guides, these rolls engaging with the rear edge of the sheet and decelerating it just prior to such delivery, finally releasing the sheet upon delivery of its front edge to the guides. For the accomplishment of the above result, both the initial delivery rolls and the front delivery rolls of the slowdown are caused to operate with identical peripheral speeds, and to conform to the same predetermined cycle of acceleration and deceleration independently of the position to which the front delivery rolls may be adjusted to accommodate varying sizes of sheets.

In certain instances where it may be desirable to accommodate sheets of widely varying length and where the variance is such that adjustment of the front delivery rolls to accommodate the shortest sheet would cause the rear end of the sheet to be released from the initial delivery rolls before engagement thereof by the front rolls, it is proposed to provide intermediate forwarding rolls which are located between the rolls heretofore mentioned and designed to maintain positive engagement and control of the sheet during that portion of its travel between the initial delivery rolls and the front or adjustable delivery rolls, these rolls also moving in synchronism in order that the sheet may be picked up and delivered without change or alteration in the rate of movement.

Still further features of the invention consist in certain novel features of construction, combinations and arrangements of parts, hereinafter described and claimed, the advantages of which will be obvious to those skilled in the art from the following description.

In the accompanying drawings illustrating the preferred form of the invention,

Fig. 1 represents a side elevation of that portion of a sheet-feeding mechanism embodying the features of the invention;

Fig. 2 is a view partially in section of the mechanism shown in Fig. 1;

Fig. 3 is a longitudinal section on the line 3—3 of Fig. 4 of the variable speed control for the delivery rolls, illustrating the manner in which the sheet is separated from a bank and delivered to the first roll;

Fig. 4 is a transverse section of the mechanism shown in Fig. 3 taken upon the line 4—4 of Fig. 3;

Fig. 5 is a detail of a portion of the mechanism controlling the speed of the delivery rolls, and illustrating particularly the mechanism partially hidden in Fig. 3;

5 Fig. 6 is a top plan view of the variable speed mechanism with a portion of the casing broken away to better show the gear train and driving arrangement; and

10 Fig. 7 is a partially diagrammatic view illustrating the employment of intermediate rolls in the event that the sheet feeder is designed for the handling of extreme size ranges.

15 Referring to the illustrated embodiment of the invention, the feeder comprises generally a frame 19 extending at its forward end in close proximity to the cylinder 12 of the press, as shown particularly in Fig. 1. At a point removed from the front end of the frame is a table or platen 14 adapted to carry the usual bank of sheets, indicated at 16. The top sheet is separated at predetermined and regular intervals from the bank in any desired manner, as by combing wheels, and delivered with the front edge of the sheet in position to be engaged by delivery rolls 18, of which at least two are employed at opposite sides of the sheet. The proper delivery of the sheet to the rolls may be controlled as is usual in machines of this type by drop guides 19 adapted to be engaged by the sheet at opposite sides and control 20 the proper presentation of the front edge to the roll. If both drop guides are engaged by the sheet, the combing mechanism is removed from operative engagement therewith. If only one drop guide is engaged by the sheet at one side, the corresponding combing rolls are removed from operative engagement, the combing rolls at the opposite side of the sheet continue to advance the sheet until that side is brought into register with the cutout, thus insuring a reasonably accurate presentation of the sheet to the delivery rolls. Mechanism for the proper presentation of the top sheet at regular intervals to the delivery rolls forms no part specifically of the present invention, and is not shown in detail herein.

30 40 45 According to the present invention, the delivery rolls 18 (only one of which is shown in each view) are positively driven at a predetermined and variable rate of peripheral speed which is properly timed with the operative movement of a complementary drop roll which engages and clamps the sheet to the delivery roll at a point in the cycle when movement of the delivery roll has momentarily ceased or substantially so. After clamping, the speed of the roll is rapidly but uniformly accelerated with a corresponding movement of the sheet, and thereafter traverses the sheet with maximum speed to a point at which the front edge of the sheet may be engaged by the mechanism of the press. Inasmuch as the sheet passes beyond the control of the delivery roll during the latter part of the travel, it is thereafter engaged by a second and similarly driven roll for governing and controlling the sheet up to its final delivery.

50 55 60 65 70 75 The mechanism for actuating the delivery roll receives its motive power from a shaft 20, as shown in Figs. 3 and 5, which is driven in any convenient manner in timed relation to the operation of the press, and if necessary to the remaining parts of the feeding mechanism, providing that these parts do not receive their motive power from the single shaft. The shaft 20 at the upper end is provided with a bevel gear 22 which meshes with and drives a second bevel gear 24 mounted upon a transverse shaft 26 which is journaled at

opposite ends in a gear casing 28. The upper end of the shaft 26 carrying the bevel 22 is supported in a yoke 30 which is removably clamped about a hub 32 for the shaft 26, as more particularly shown in Figs. 4 and 5. Loosely journaled upon a second and parallel shaft 33 is a large gear 34 which meshes with a small gear 36 pinned to the shaft 26 and is driven thereby. The large gear carries two planet gears 38 and 40, each loosely journaled upon a bearing mounted in the face of the large gear 34, and in turn meshing with a common sun gear 42 which is provided with an elongated hub portion 44 in which the shaft 33 is journaled, the sun gear being stationary and causing rotation of the planet gears as carried thereabout in a circumferential direction by the continuous and uniform rotation of the carrying gear 34. Each of the planet gears 38 and 40 carried at diametrically opposite sides of the gear 42 is provided with a crank, these cranks being indicated respectively at 46 and 48, and driving a variable speed gear 50 through links 52 and 54, as indicated more particularly in Figs. 4 and 5. It will be noted that the diameter and pitch circumference of the gears 34 and 50 are identical, and that with the mechanism illustrated, the two gears accomplish one complete revolution simultaneously. It will be furthermore evident, however, that owing to the variable drive connection between the constant speed gear 34 and the variable speed gear 50, the motion of the variable speed gear is accelerated and decelerated twice during each complete rotation of the gear 34, due to the fact that the sun gear 42 is twice the size of the planet gears 38 and 40, causing each of these gears to make two complete rotations during a complete circumferential movement about the periphery of the sun gear. Owing to the arrangement of the crank arms and the connections between the crank arms and the gear 50, the movement of the gear 50 is momentarily reduced at two points in the rotation to practically a standstill, and therebetween is uniformly accelerated by the cranks to a rate of speed slightly in excess of the driving gear 34. Obviously due to the arrangement of the crank arms and the diametrically opposite disposal of the planet gears and cranks, the acceleration and deceleration, due to the opposite planet gears, take place simultaneously, and uniform and similar driving torques are simultaneously exerted upon the gear 50. As will be evident from Fig. 4, the gear 50 is provided with a hub 60 which is loosely journaled upon the stationary hub 44. Variable rotation of the gear 50 is transmitted through a small pinion 62 mounted on a transverse shaft 64 which carries a second pinion 66 which in turn drives a gear 68 mounted upon the roll shaft 70 and serving to drive it directly. The same varying speed is transmitted to a feed shaft 72 from the roll shaft 70, as follows: A gear 74 is mounted upon the roll shaft at the opposite side of the frame from the gear 68, and meshes with a larger idler gear 76 which is loosely journaled upon a stub shaft 78. This idler gear engages with and drives a small pinion 80 upon a shaft 82 which carries a helical gear 84 at its outer end, which in turn meshes with and drives a helical gear 86 pinned to the drive shaft 72. The drive shaft 72, as indicated more particularly in Fig. 2, extends lengthwise of the bed, and is provided with a sliding helical gear 87 keyed thereto for sliding movement thereon with the carriage 88, which carries a front delivery roll 90. This roll is journaled in the carriage upon a shaft 92, and is

driven from the helical gear 87 by virtue of a second helical gear 94 mounted upon the roll shaft. By a proper coordination of the gear ratios included in the train of gears 74, 76 and 80, the delivery rolls 18 and 90 of dissimilar diameter may be rotated at the same peripheral rate of speed. Obviously the rate of peripheral speed is varied simultaneously, due to the common variable driving connection. From an inspection of Figs. 1 to 10 3, it will be evident that the carriage 88 carrying the slowdown assembly is slidably mounted upon inclined guide members 96, and is adjustably moved lengthwise of the guide members through the provision of gears 98, meshing with oppositely disposed racks 100, shown in Figs. 1 and 2, which are respectively a side elevation and a sectional elevation taken approximately centrally of the feeding apparatus. Movement of the carriage into position to accommodate different lengths 20 of sheet is accomplished by rotation of an adjusting member 102 which causes the carriage to be traversed lengthwise of the racks. The carriage is locked in adjusted position by a clamping member 104 to lock the gear shaft against 25 rotation. After the carriage has been adjusted to properly locate the front delivery rolls for any given size of sheet, a stop collar 106 may be clamped to the guide rail to determine the position of the carriage and to permit its invariable 30 return to the same point if for any reason whatsoever it is desired to temporarily retract the carriage and assembly carried thereby. Cooperating with each of the front delivery rolls is a presser roll 110 mounted upon the free end of an arm 112 which is capable of rocking movements on the shaft 114 carrying the gears. The roll is normally maintained yieldingly in contact with the delivery roll therebeneath by virtue of a spring 116 stretched between connecting members 118 and 120, mounted respectively upon the hub of 40 the arm 112 and a normally fixed sleeve 122, which is, however, capable of initial adjustment about the shaft by loosening the clamping screw 124. With this construction, the presser rolls are normally maintained in operative contact with 45 the delivery rolls to cause instant engagement and forwarding of a sheet from the primary rolls 18. Cooperating with the primary delivery rolls 18 are drop or clamping rolls 130 which are mounted upon the free ends of arms 132 rotatably supported on the shaft 82. The hub of the arm 132 is connected with a cam lever assembly 136 through a sleeve 138, as shown more particularly 50 in Fig. 4. The outer end of the cam lever 136 is provided with a roll 140 which rides upon a peripheral cam 142 pinned to a shaft 144, which as shown in Fig. 4 forms a virtual extension of the shaft 33, being connected to rotate with this shaft through the hub 146 pinned thereto and 55 the hub 148 which are interlocked at 150. The hub 148 forms a part of a grooved wheel 152 engaged by a friction belt 154, this belt being fixedly connected at opposite ends to apply friction to the wheel. This wheel is normally driven 60 from the constant speed gear 34 through a pawl 168 engaging in a tooth 162 formed in a boss 164 mounted on the face of the wheel, and retained in engagement therewith by a spring 166 connected to the wheel 152, all as shown more particularly in Fig. 5. By virtue of this construction, the shaft and friction wheel mounted thereon, together with the drop roll cam 142, are normally driven with the constant speed gear 34, but if so desired the gear and connected train 65 may be retracted or reversed without corre-

spondingly operating the friction wheel drop rolls and operating mechanism.

Referring to the drop rolls 130, it will be evident from an inspection of Figs. 3 and 4, that the lever 136 is compounded in two parts, consisting of a main supporting arm 168 projecting from the sleeve 138 and having pivoted midway thereof a second lever arm 170. The main arm 168 carries a pin 172 which bears upon the upper portion of the lever 170, and maintains the latter 16 in contact with the cam 142. A spring 174 connected with the main arm 168 serves to apply the requisite pressure to the drop roll when in operative position. The purpose of compounding the main assembly 136 is to obtain the requisite 15 fine adjustment of the movement of the drop roll into operative position. This is accomplished by mounting the arm 170 upon an eccentric support 176 journaled in the arm 168, and as indicated in Figs. 3 and 4 capable of rotative adjustment through a member 178, and locked in adjusted position by a locking member 180, all as indicated clearly in Figs. 3 and 4. The drop roll arm 132 is connected with the sleeve 138 through 20 a spring 182, which is connected with an extension 184 extended from a hub 186 clamped to the sleeve. By virtue of this construction the main spring 174 causes a sudden and instant movement of the drop roll into operative position in contact with the delivery roll therebeneath, and thereafter the light pressure spring 25 182 serves to govern the pressure of the drop roll upon a sheet of paper. By virtue of this adjustment of the drop roll, the engagement and delivery of the sheet to the drop guides of the 30 press may be predetermined with extreme nicety, and the movements properly coordinated and accurately timed.

Now referring to the operation of the mechanism, it will be evident that a sheet of paper 40 is separated from the top of the bank 16 by comber rolls, as indicated at 200 or their equivalent, and advanced with the front edge in position to be engaged between the nip of the delivery rolls 18 and complementary drop rolls. If 45 the front edge of the sheet is presented properly to the delivery rolls at opposite sides, both detector fingers 20 function in the usual manner to cause removal of the comber wheels into inoperative position; otherwise, one set of comber 50 wheels continues operating until the front edge of the sheet is trued up. With the sheet positioned with its front edge in position to be engaged by the delivery rolls and substantially 55 stationary, the drop rolls through the cam mechanism previously described are depressed into contact with the delivery rolls and the sheet nipped thereby. At this point in the operation, the peripheral speed of the delivery rolls is slowed down to practically a standstill or thereabouts, 60 and after engagement of the front edge of the sheet, the speed of the delivery rolls and the sheet carried thereby is uniformly accelerated to a maximum and thereafter maintained during the major portion of the sheet movement. 65 Before passage of the rear edge of the sheet from the delivery rolls 18, the front edge of the sheet is engaged by the front rolls 90 having a peripheral speed corresponding to the rate of travel of the sheet picked up thereby without any 70 change of rate whatever, so that the sheet is completely within the control of the front rolls before release by the delivery rolls 18. This continues until the front edge of the sheet has reached a predetermined position in proximity 75

to the usual pull-up guides at the delivery end of the feeder. When thereafter and as the tail end of the sheet is about to leave the rolls 90, the latter are decelerated and the motion of the sheet slowed down to practically a complete standstill for immediate delivery to the pull-up guides. This cycle of operations accounts for approximately one-half a revolution of the main gears, and the next and succeeding sheet is not picked up and engaged by the delivery rolls, except during every second slowdown of the rolls. In other words, the passage of a sheet from the delivery rolls to the pull-up guides is completed in substantially one-half a revolution of the main gear 34. The front edge of the sheet is delivered in accurate register with the drop guides 210 of the press by the front pull-up guides 212 operating in the usual manner. The stopping of the machine in the event that no sheet is present is controlled by a throw-off finger 214. As the operating mechanism for these devices is well known and common in the art and forms no part of the present invention, it is not described specifically herein. It will suffice to say in this connection that the position of the tail-end slowdown rolls is so adjusted as to release the sheet just prior to the instant at which the front edge is engaged by the pull-up guides, the advancing movement of the sheet having been practically stopped at this time.

In the event that the feeding mechanism is of sufficient size to accommodate the largest sheet which may be encountered, it is necessary for the purpose of properly handling sheets of minimum size to provide intermediate forwarding rolls in addition to the tail-end slowdown. This can be understood if it is considered that the feeding mechanism is of sufficient size to accommodate a sheet approximating 41 inches in length which may be considered as the largest sheet normally encountered. In this case obviously the span between the pick-up delivery rolls and the pull-up guides must exceed the length of the sheet sufficiently to permit passing of sheet control completely to the tail-end slowdown prior to the delivery of the front edge to the guide. If a sheet of minimum size is then to be operated upon with the same mechanism, the tail-end slowdown must be advanced forwardly toward the guides to a position at which the rear edge of the sheet will be controlled just prior to the delivery of the front edge to the pull-up guides. This means that the span between the slowdown rolls and the pull-up guides will approximate 18 inches, leaving a span greater than the width of the sheet between the delivery rolls and the slowdown rolls. To maintain complete control of a small sheet under these conditions, a set of intermediate forwarding rolls are provided as shown in Fig. 7 of the drawings. These intermediate rolls are indicated at 220 cooperating with a pressure roll 222, and are mounted upon the inclined guides between the delivery roll 13 and the slowdown roll 90. The intermediate roll, as indicated, is operated in synchronism with the complementary handling rolls through inter-

meshing helical gears 224 and 226, the latter gear being splined to the feed shaft 72.

What is claimed is:

1. Sheet-feeding mechanism comprising a rotary actuating member, stationary gear, planet gears journaled upon the actuating member at diametrically opposite points and revolving about the stationary gear, a crank connection rotated by each planet gear, a driven member, links connecting each of the cranks in the driven member in a manner such that the cranks are oppositely directed at all times, and means for rotating the actuating member to impart a constantly varying movement to the driven member through the planet gears and operating connections. 15

2. Sheet-feeding mechanism comprising an actuating gear, planet gears journaled thereon at diametrically opposite points, a stationary sun gear interposed between the planet gears and having double the number of teeth in each of the planet gears, a driven gear, crank connections between the planet gears and driven gear to impart a predetermined and variable rate of rotation to the driven gear, a delivery roll, and connections between the driven gear and roll 25 designed to traverse any peripheral point of the roll through a distance approximately equal to the length of travel of the sheet during each half revolution of the driven gear.

3. Sheet-feeding mechanism comprising driving and driven gears, means for operating the driving gear at a constant rate of speed, connections between the driving and driven gears for slowing down and momentarily stopping the driven gear twice during each complete revolution thereof, a delivery roll, front guides, and connections between the driven gear and roll designed to engage and substantially complete the advance of the sheet to the front guides between slowdown periods of the roll. 40

4. Sheet-feeding mechanism comprising front drop guides, forwarding rolls arranged to engage and forward the sheet, means for operating the forwarding rolls at a predetermined rate of rotation, a delivery roll, means for actuating the delivery roll at a predetermined rate of rotation, a drop roll cooperating therewith, an arm supporting the drop roll, a compound lever connected with the arm, a cam for operating the lever, and an eccentric member for varying the two parts of the compound lever to correspondingly vary the motion of the drop roll created by the cam. 45

5. Sheet feeding mechanism comprising separating means, delivery rolls receiving the sheet therefrom, pull-up guides, and means for rotating the delivery rolls at a variable speed timed in relation to the presentation of the sheet edge thereto, the rolls being operated at the lowest peripheral speed at the moment of presentation, rapidly accelerating to a maximum speed, conveying the sheet edge at maximum speed throughout the major portion of its traverse to the pull-up guides and finally decelerating the movement of the sheet to an approximate stand-still upon actual delivery to the pull-up guides. 55 60

HENNING HALLSTREAM. 65
